UNITED STATES PATENT OFFICE

150,088

DESIGN FOR A COMBINATION ROCKING
CHAIR, STRAIGHT CHAIR, AND TRAY
CHAIR FOR INFANTSRobert O. Meyer and Frank L. Stretz,
Kansas City, Mo.

Application July 22, 1946, Serial No. 131,818

Term of patent 3½ years

(Cl. D15—1)

To all whom it may concern:

Be it known that we, Robert O. Meyer and Frank L. Stretz, citizens of the United States, residing at Kansas City, in the county of Jackson and State of Missouri, have invented a new, original, and ornamental Design for a Combination Rocking Chair, Straight Chair, and Tray Chair for Infants, of which the following is a specification, reference being had to the accompanying drawing, forming a part thereof.

Figure 1 is a perspective view of the combination rocking chair, straight chair, and tray chair for infants, with the same in condition for use as a rocking chair, showing our new design.

Fig. 2 is a perspective view showing the chair in condition for use as a rocking chair with tray accessible to the occupant, and

Fig. 3 is a perspective view showing the chair in condition for use as a straight chair and

Fig. 4 is a perspective view showing the chair

in condition for use as a straight chair with tray available to the occupant.

We claim:

The ornamental design for a combination rocking chair, straight chair, and tray chair for infants, as shown.

ROBERT O. MEYER.
FRANK L. STRETTZ.
